Primary Examiner — Amy C Wierenga*Assistant Examiner* — Grace Doyle(74) *Attorney, Agent, or Firm* — Brooks Kushman P.C.(57) **CLAIM**

The ornamental design for a planter as shown and described.

DESCRIPTION

FIG. 1 is a front elevation view of a planter;

FIG. 2 is a top plan view thereof;

FIG. 3 is a left side elevation view thereof;

FIG. 4 is a right side elevation view thereof;

FIG. 5 is a rear elevation view thereof;

FIG. 6 is a bottom plan view thereof;

FIG. 7 is a front, top and right side perspective view thereof; and,

FIG. 8 is a front, bottom and right side perspective view thereof.

The dot-dash boundary lines define bounds of the claim and form no part thereof. The portions of the planter shown in evenly spaced broken lines form no part of the claimed design.

1 Claim, 8 Drawing Sheets(56)
